ELECTRIC CONTROL SYSTEM

Hugh E. Young, Chicago, Ill.

Application June 20, 1932, Serial No. 618,369

15 Claims.

(Cl. 176—8)

This invention provides a new system and method for controlling the effective applied voltage from a source of alternating current to keep the effective flow of current per unit of time 5 through a load substantially constant, even though the effective resistance of the load to current flow may vary from substantially short circuit value to maximum load, i. e., maximum effective resistance for which the system is de- 10 signed.

The principal feature of my invention is the provision of means for maintaining the current substantially constant regardless of variations in the line load. My invention is particularly use- 15 ful in connection with street lighting systems; wherein a relatively large number of lamps are connected in series. My invention is not to be limited to a lamp load, but is applicable equally to any situation wherein the load changes either 20 by cutting in or out or otherwise changing resistance or reactance or counter-electromotive force, or any other known opposition to current flow.

According to my invention, the applied voltage 25 is initially made great enough to force the desired current through the resistance or opposition of the load when it is greatest. Then, as the resistance or opposition to current flow becomes or is made less, the current tends to rise, 30 but is effectively limited through the employment of a tube, the firing time of which per half cycle is so controlled by the current flow produced as to select the desired voltage and its period of application as will keep the effective 35 current flow per unit of time through the load substantially constant for all variations within the design of the system.

In the preferred practice of my invention, the tube is a grid controlled arc rectifying tube disposed between the anode transformer and the load circuit in which predetermined current flow is to be maintained. By the employment of a current sensitive regulator, the phase of grid excitation is made shiftable through substantially 45 180 electrical degrees as the effective resistance or opposition to current flow shifts from maximum toward minimum. Thus, no matter what the effective resistance or opposition to current may be, the tube supplies automatically 50 the necessary or proper part of each half cycle to keep the effective current flow per unit of time substantially constant.

As a modification, the tube, instead of being directly between the alternating current line and 55 the load, may be disposed in a control circuit,

the current through which is so regulated and applied to a saturable core reactor in the load circuit as to keep the current in the load circuit constant over a like range of load resistance variation, i. e., from maximum to substantially 5 short circuit value.

Other features and advantages of my invention will appear more fully as I proceed with my specification.

In those forms of device embodying the features of my invention shown in the accompanying drawings—

Figure 1 is a diagrammatic view showing my invention employed in a system with direct current distribution; and Fig. 2 is a modified view 15 showing the application of the invention to a system with alternating current distribution.

It is to be understood that all the drawings are diagrammatic views, in which no attempt is made to show the necessary and usual fuses, 20 cut-outs, relays, protective devices, and the like, commonly used in electrical systems of the character herein described.

In the device of Fig. 1, 10, 10 indicate the A. C. supply, 11 the load circuit with lights 12, 12 connected in series. The lights 12, 12 may be either of the incandescent, glow or the arc discharge type, the incandescent type being preferred. It is to be understood, of course, that in connection with each light, there is provided 25 the customary automatic cut-out or short circuiter (not shown) to prevent interruption to the line flow when the light burns out or is turned out. It will be seen that with the lights connected in series, as shown, the resistance, and consequently the load of the line will vary, depending upon the number of lights in use. 30

In a system of the kind just described, I provide means for maintaining the current substantially constant regardless of variations in the line load. I shall now describe the construction and operation of such means. 13, 13 indicate rectifying tubes of the three-element type well known in the electrical arts. 13^a, 13^a indicate the filaments, 13^b, 13^b the grids and 13^c, 13^c the anodes of tubes 13, 13. 14 indicates a transformer for supplying current to heat the filaments 13^a, 13^a. 15 indicates a grid transformer for supplying voltage to the grids 13^b, 13^b. One end of primary winding P of grid transformer 15 is connected to line 11 by line 17, the other end of this winding being connected by line 18 to the common connection of resistance 23 and coil of solenoid 19. The secondary S of grid transformer 15 has its ends connected to grids 13^b, 13^b by lines 16, 16, while 45 50 55

the center tap of this winding is connected to line 11 by line 20. 29 indicates the anode transformer which supplies voltage to anodes 13^c, 13^c of tubes 13, 13. The primary P of anode transformer 29 connects to the supply lines 10, 10. The secondary S of anode transformer 29 has its ends connected to anodes 13^c, 13^c of tubes 13, 13, while its center tap connects to load circuit 11 through the coil of D. C. solenoid 20. Intermediate taps T1, T2 are connected to resistance 23, and coil of solenoid 19, respectively. 19 indicates the A. C. solenoid with an iron plunger 19^a, constituting a variable inductance. 20 indicates a series D. C. solenoid with an iron plunger 20^a. The plungers 19^a and 20^a are connected to opposite ends of lever 21 which is pivoted, as shown. 22 indicates a spring, and 22^a a thumb nut for adjusting tension of spring 22 so as to obtain an electrical balance of lever 21. 23 indicates a resistance, one end of which is connected to tap T, of secondary S of anode transformer 29, and the other end to coil of solenoid 19.

In the apparatus of Fig. 1 the tubes 13, 13 are of the rectifying type with grid control. Control is effected by applying A. C. voltage to both the anodes, 13^c, 13^c and the grids 13^b, 13^b. The average current flowing can be controlled by varying the grid voltage with respect to the anode voltage, for example, as here shown, this is accomplished by varying the phase of the grid voltage with respect to the phase of the anode voltage. For example, as here shown, this varying is obtained by splitting the phase. In the operation of the apparatus, as the line load or resistance decreases (for example, by burning out and short-circuiting of one or more lights 12) the current tends to increase, and as this load current flows through the D. C. series coil of solenoid 20, the increased magnetic pull on plunger 20^a pulls this plunger further upward into the coil, and through pivoted lever 21, the plunger 19^a of A. C. solenoid 19 is pushed further down into the coil, and this additional iron within the coil increases its inductance. The transformer 15 reverses the polarity of the split phase so that the grid voltage polarity will be the same as the plate voltage polarity. This increase in inductance shifts or splits the phase of the grid voltage with respect to the anode voltage in a direction (more out of phase) which prevents an undue increase of load current. Should the load current tend to decrease, from any cause, the decreased magnetic pull on plunger 20^a of solenoid 20 will permit spring 22 to pull it down and through action of lever 21, plunger 19^a of solenoid 19 will be pulled upward. This removal of iron from within the coil 19 reduces its inductance, and this change in inductance shifts the phase of the grid voltage with respect to the anode voltage in a direction (more in phase) which prevents an undue decrease of load current. The load current is thus held substantially constant under all conditions.

Due to the fact that no appreciable current flow is required in the grid excitation circuit, the mass of the moving core 19 and the distance it is required to travel may be made quite small. The solenoid 20 may be as sensitive as desired. Hence, with the present regulator, the phase of grid excitation may be changed with such rapidity that as soon as the magnetic effect upon the solenoid core 20^a is changed, even within the half cycle, the regulator promptly shifts the phase angle of excitation to avoid the injurious effect of excessive current flow for any greater time than

the completion of a half cycle which has already begun to flow due to firing of the tube.

The regulator of my invention has in connection with the present form of phase shifting circuit a marked advantage not found in prior devices. It is to be observed that the regulator comprises a magnet such as a solenoid having the movable member, in this case the core 20^a and directly connected thereto by the lever 21, a movable part of a reactance 19. The movable part in this case is the core 19^a. The reactance part 19^a creates by its movement a voltage in the reactance branch T². This voltage is independent of the increase or decrease due solely to its change of position, and is something additional caused by the movement itself. The movement of the core 19^a in the coil induces a voltage which affects the grid excitation. As a result, the response is sharper and more rapid than it is possible to secure in known devices. The small inertia of the parts of the regulator and the consequent rapid movement due to variations in current in the direct current circuit aids in instantaneous response. Tests of my system show a uniformity or constancy of effective current flow in the lamp circuit such that with a sensitive ammeter in series with the lamps, no detectable variation occurs as the lamps are successively all switched in or out of the series circuit.

The device of Fig. 2 shows the invention applied to apparatus in which A. C. power is delivered to the line 111. In this apparatus, I use a saturable core reactor 126 the A. C. coil 126^a of which is in series with the solenoid 120 and the load 112. I then employ rectifying tubes similar to the rectifying tubes 13, 13 to supply D. C. to the D. C. coil of the reactor. The rectifying tubes are provided with control grids and the grid voltage with respect to the anode voltage is varied by variations in the line current in a manner similar to the way in which the grids of the tubes 13, 13 are controlled. The result of this is to vary the flow of D. C. through the D. C. coil of the reactor, thus varying the inductance of the A. C. coil thereof. The apparatus is so arranged that a tendency for the line load to increase will increase the inductance, and vice versa. Thus, the line current is maintained substantially constant, even though the load varies.

In the device of Fig. 2, the wires 110, 110 indicate the A. C. supply. 111 indicates the A. C. series load circuit which is in series with coil 126^a of reactor 126, the load thereon comprising the series connected lights 112, 112 which may be either of the incandescent, glow or arc discharge type.

In a system of the kind just described, I provide means for maintaining the current substantially constant regardless of variations in the line load. I shall now describe the construction and operation of such means. 113, 113 indicate the rectifying tubes which are of the three-element type. 113^a, 113^a indicate the filaments, 113^b, 113^b the grids and 113^c, 113^c the anodes of tubes 113, 113. 114 indicates the transformer for supplying current to heat the filaments 113^a, 113^a of tubes 113, 113. 115 indicates the grid transformer for supplying voltage with reverse polarity to the grids 113^b, 113^b of tubes 112, 113. One end of primary winding P of grid transformer 115 is connected to line 127 by line 117, and the other end of this winding is connected by line 118 to the common connection of resistance 128, and coil of solenoid 119. The secondary S of grid transformer 115 has its ends connected to

grids 113^b, 113^b by line 116, 116, while the center tap of this winding is connected to line 127 by line 128. 128 indicates the anode transformer which supplies voltage to anodes 113^c, 113^c of tubes 113. The primary P of anode transformer 128 connects to the supply lines 116, 116. The secondary S of anode transformer 128 has its ends connected to anodes 113^c, 113^c, while its center tap connects to D. C. circuit 127 through D. C. coil 126^b of reactor 126. Intermediate taps T₁, T₂ are connected to resistance 123 and coil 119 of solenoid 119, respectively. 119 indicates the A. C. solenoid with an iron plunger 119^a, constituting a variable inductance. 120 indicates the A. C. solenoid with iron plunger 120^a, the winding of which is in series of load circuit 111 and A. C. coil 126^a of reactor 126. The plungers 119^a and 120^a are connected to opposite ends of lever 121 which is pivoted as shown. 122 indicates the 20 spring, and 122^a a thumb nut for adjusting tension of spring 122 so as to obtain an electrical balance of lever 121. 123 indicates a resistance of a correct ohmage which may be adjustable, one end of which is connected to tap T₁ of secondary S of anode transformer 128, and the other end to coil solenoid 119. 126 indicates a saturable core reactor with core legs and coils so arranged that there is no transformer action between the two windings. No attempt is made in 30 the diagram of Fig. 2 to show construction details of this reactor. Coil 126^a is the A. C. winding of reactor 126, and being in series with line 111 carries the full load of the series circuit. Coil 126^b is the D. C. winding of reactor 126 and carries the rectified full wave direct current supplied by the rectifying tubes 113, 113. Coil 126^b of the reactor is connected in series with D. C. circuit 127.

In the apparatus of Fig. 2, the tubes 113, 113 are 40 of the rectifying type with grid control. Control is effected by applying A. C. voltage to both the anodes 113^c, 113^c and the grids 113^b, 113^b. The average current flowing can be controlled by varying the phase of the grid voltage with respect to the anode voltage. In the operation of the apparatus, if sufficient direct current is passed 45 through coil 126^b of reactor 126 to saturate its core, the inductance of A. C. coil 126^a will be greatly reduced and circuit 111 with its load 112 will have minimum impedance (resistance to current flow). With no direct current flowing in coil 126^b of reactor, A. C. coil 126^a will act as an iron cored choke and circuit 111 with its load 112 will have its greatest impedance (resistance to current 50 flow). With any intermediate amount of direct current flowing in coil 126^b, the inductance or choking effect of coil 126^a will vary, depending upon the amount of direct current flowing in coil 126^b. With all adjustments made and the required 55 current flowing in line 111, if the line load or resistance decreases (for example, by burning out and short-circuiting of one or more lights 112) the current tends to increase in circuit 111, but since the coil of A. C. solenoid 120 is in series with load circuit 111, the increased current exerts a stronger magnetic pull on iron plunger 120^a pulling it upward within the coil. Through the pivoted lever 121, the upward motion of plunger 120^a pushes iron plunger 119^a of solenoid 119 further downward within its coil, thus increasing the inductance of coil 119. This increase of inductance shifts or splits the phase of the grid voltage with 60 respect to the anode voltage in a direction (more out of phase) so that less direct current flows in coil 126^b of reactor 126. The decrease of direct

current in coil 126^b increases the inductance, or choking effect of coil 126^a sufficiently to prevent any undue increase in load current. If the current in the load circuit 111 should tend to decrease, from any cause, the decreased magnetic 5 pull on iron plunger 120^a of solenoid 120 will cause spring 122 to pull down this end of pivoted lever 121, thus raising plunger 119^a slightly out of coil 119 which decreases its inductance. This decrease of inductance shifts or splits the phase of 10 the grid voltage with respect to the anode voltage in a direction (more in phase) so that more direct current flows, in D. C. coil 126^b of reactor 126. This increase of direct current decreases the inductance or choking effect of A. C. coil 126^a sufficiently to prevent any undue decrease in the load current. Thus a substantially constant current 15 will be maintained regardless of variations in the load circuit.

While I have shown a specific embodiment in 20 which the load comprises lamps, the opposition of which to current flow is chiefly resistance, it is to be understood that I do not intend to confine the invention to any specific load, nor any specific form of resistance to current flow, as obviously 25 the specific form of the load or its particular form of opposition of current flow may be varied without departure from my invention.

While I speak herein of constant current, it is 30 not intended, as those skilled in the art appreciate, that the fluctuations due to current impulses must be smoothed out. I intend the phrase constant current to mean that the effective current per unit of time is constant or near enough constant for the purposes intended.

While I have shown and described certain embodiments of my invention, it is to be understood that it is capable of many modifications. Changes, therefore, in the construction and arrangement may be made without departing from 40 the spirit and scope of the invention as disclosed in the appended claims, in which it is my intention to claim all novelty inherent in my invention as broadly as permissible, in view of the prior art.

It is to be noted that since the apparatus of 45 Fig. 1 is designed to give a constant average current, the spring 22 serves to substantially balance the pull of the solenoid 20 upon the armature 20^a for all positions of said armature in its range of movement when a predetermined current is flowing 50 in the solenoid. For example, if it is desired to maintain the D. C. output substantially constant at say 6 amperes, the spring 22 will substantially balance the pull of the solenoid on the armature 20^a when 6 amperes is flowing through 55 the solenoid coil. Moreover, this balancing will occur at substantially all positions of the armature in its range of movement. Consequently, if there is any momentary change in the current flow, the armature will move until such predetermined flow of 6 amperes is again established (through a change in the inductance 19), whereupon the armature will stop in its new position again balanced by the spring.

What I regard as new, and desire to secure 65 by Letters Patent, is:

1. A system for current regulation comprising an A. C. supply circuit, a work circuit the resistance of which is variable, said work circuit being supplied with energy from said supply circuit, a saturable core reactor for controlling the energy supplied through it to said work circuit, a grid controlled tube having its plate current supplied by said supply circuit and having a direct current circuit connected to said reactor to sat- 75

urate the core thereof to variable degree, a grid control circuit for supplying grid excitation for said tube, and means including a phase shift circuit and a regulator in series relation to the 5 work circuit for shifting the phase of grid excitation to regulate the flow of current in said work circuit.

2. The system of claim 1 wherein the regulator comprises a magnet having a movable member 10 and a stationary member and the phase shift circuit includes a resistance element and a reactance element one of said elements being adjustable with respect to the other element, and a direct mechanical connection between said 15 movable member and said adjustable element.

3. In an electrical system of distribution of the class wherein an alternating current source energizes a work circuit that is variable over a wide range of load resistance, the combination with 20 said system of a pair of electric valves interconnected between said source and said work circuit, said electric valves being connected to conduct successive half cycles of the alternating current, a control electrode in each of said valves, 25 phase shift means energized from said alternating current source for energizing said control electrodes to render said valves conducting at predetermined times in the half cycles of alternating current to be conducted thereby, and 30 means connected to be directly responsive to the current flow variation in said load circuit for controlling said phase shift means in such manner as to change the time in each half cycle at which said valves are rendered conducting 35 for maintaining the load current substantially constant regardless of change of said resistance.

4. In an electrical system of distribution of the class wherein an alternating current source energizes a work circuit that is variable over a 40 wide range of load resistance, the combination with said system of a pair of electric valves interconnected between said source and said work circuit, said electric valves being connected to conduct successive half cycles of the alternating 45 current, a control electrode in each of said valves, a phase shifting circuit comprising a resistor and an adjustable reactor energized from said alternating current source and connected to said control electrodes to render said valves conducting 50 at predetermined times in the half cycles of alternating current to be conducted thereby, a winding connected in series circuit relation with said load circuit, and means responsive to current flow variation through said winding corresponding to 55 change in resistance of said load circuit for controlling said adjustable reactor in such manner as to change the time in each half cycle at which said valves are rendered conducting for maintaining the load current substantially constant 60 regardless of change of said resistance.

5. An electric power system comprising, in combination, a pair of electric valves for connection between a source of alternating current and a load circuit requiring substantially constant current the resistance of which is variable over a wide range, said electric valves being connected to conduct successive half cycles of the alternating current, a control electrode in each of said valves, a phase shifting circuit comprising 65 a resistor and a reactor connected in series circuit relation for energization from said alternating current source, said phase shift circuit being connected to said control electrodes to render said valves conducting at predetermined times 70 in the half cycles of alternating current adapted

to be conducted thereby, a movable core in said reactor, a winding connected in series circuit relation with said load circuit, a movable core in said winding, a spring for biasing said last named movable core against the force exerted thereon by said winding, and a pivoted arm interconnecting said cores for moving said first named core in accordance with current flow variation in said winding to change the inductance of said reactor in such manner as to change the time in each half cycle at which said valves are rendered conducting for maintaining the load current substantially constant regardless of change of said resistance. 5

6. An electric power system comprising, in combination, a transformer having a primary winding for connection to a source of alternating current and a secondary winding provided with a mid-tap; a pair of electric valves each having an anode, a cathode and a control electrode; 20 the anodes of said valves being connected to the terminals of said secondary winding and the cathodes being disposed to be commonly connected to one terminal of a load circuit requiring substantially constant average current the resistance of which is variable over a wide range, the other terminal of said load circuit being connected to said mid-tap; a phase shifting circuit comprising a resistor and a reactor connected in series circuit relation for energization from said 25 alternating current source, said phase shift circuit being connected to said control electrodes to render said valves conducting at predetermined times in the half cycles of alternating current adapted to be conducted thereby, a movable core 30 in said reactor, a winding connected in series circuit relation with said load circuit, a movable core in said winding, spring means for biasing said last named movable core against the force exerted thereon by said winding, and a pivoted 35 arm interconnecting said cores for moving said first named core in accordance with current flow variation in said winding to change the inductance of said reactor in such manner as to change the time in each half cycle at which said valves 40 are rendered conducting for maintaining the average load current substantially constant regardless of change of said resistance. 45

7. In a series lighting system, an alternating current supply system, a load circuit including 50 a plurality of series connected lamps joined to said supply system; a reactor having an alternating current coil connected in series with said load circuit and a direct current coil, a rectifying tube for delivering direct current to said direct 55 current coil, and means for causing variations in said load circuit to vary the flow of direct current in said direct current coil by changing the phase of the grid voltage with respect to the anode voltage of the rectifying tube. 60

8. In a series lighting system, an alternating current supply system, a load circuit including 65 a plurality of series connected lamps joined to said supply system, a reactor having an alternating current coil connected in series with said load circuit, a direct current coil on said reactor, a rectifying tube for delivering direct current to said direct current coil, means for changing the phase of the grid voltage with respect to the anode voltage of said rectifying tube including a grid 70 voltage circuit with inductance and resistance therein, and means whereby variations in the load current vary the inductance. 75

9. In a series lighting system, an alternating current supply system, a load circuit including

- a plurality of series connected lamps joined to said supply system, a reactor having an alternating current coil connected in series with said load circuit, a direct current coil on said reactor, 5 a rectifying tube for delivering direct current to said direct current coil, and means for causing variations in said load circuit to vary the phase of the grid voltage with respect to the anode voltage of the rectifying tube to vary the flow 10 of direct current in said direct current coil, said means including a grid voltage circuit with variable inductance and resistance therein, a solenoid in series with said load circuit, and a connection between the solenoid and the inductance 15 whereby an increase of current in the solenoid tends to increase the inductance, and vice versa.
10. The method of maintaining constant the effective value of current in a load circuit energized from an alternating current source through 20 a rectifying tube, the resistance of the load circuit being variable from maximum to substantially zero value, which comprises firing the tube for each similar half cycle, and delaying the time of firing within each half cycle as the resistance 25 of the load circuit decreases from the maximum to the zero value in accordance with the increase in current flow in the load circuit from the constant value.
11. The method for maintaining substantially 30 constant the flow of current in a load circuit from an alternating current source through a grid controlled rectifying tube, the resistance of which load circuit is variable from a maximum value to a substantially zero value, which comprises 35 applying a firing potential to the grid for each similar half cycle of alternating current applied to the tube to fire the tube, and delaying during the half cycles the time at which the firing potential is applied as the resistance of the load 40 circuit decreases from the maximum to the substantially zero value in accordance with the increase in current flow in the load circuit from the substantially constant value.
12. The method of maintaining substantially 45 constant the flow of direct current through a grid controlled rectifying tube from an alternating current source to a load circuit the resistance of which is variable from a maximum value to a substantially zero value, which comprises 50 applying alternating current firing potential to the grid of the same frequency as applied to the anode of the tube to cause unidirectional current to flow in the load circuit, and altering the phase 55 relation between the potential applied to the grid and those applied to the anode as the resistance of the load circuit changes between said maximum and said substantially zero values in accordance with the change in direct current flow in the load circuit from the substantially constant flow to maintain the flow substantially constant.
13. In an electrical system of distribution of 60 the class wherein an alternating current source energizes a work circuit, the combination with said system of a grid controlled arc rectifying tube connected between said source and said work circuit, means for exciting the grid of said tube from said source; means for controlling the phase of the grid excitation comprising a resistance element, a reactance element and a circuit controlled by adjustment of one of said elements with respect to the other, one of said elements being adjustable; and a current sensitive device
- connected to be responsive to the current in the work circuit, said current sensitive device having a movable member, said movable member and said adjustable element being coupled mechanically to permit the adjustable element to be 5 shifted by said movable member to shift the phase of the excitation applied to said grid to limit the current flow in said work circuit to a predetermined value regardless of the change in resistance thereof between said maximum and 10 said zero resistance values.
14. In an electrical system of distribution of the class wherein an alternating current source energizes a load circuit including devices such as 15 series incandescent lamps, glow and arc discharges requiring substantially constant current for circuit stability, the combination with said system of an anode transformer having a primary winding for connection to said source and a secondary winding with a mid-tap for connection 20 to one terminal of said load circuit; a pair of grid controlled arc rectifiers, each having an anode, a cathode, and a control grid; the anodes being individually connected to the terminals of said secondary winding and the cathodes being commonly connected to the other terminal of said load circuit; a current sensitive device connected 25 in series circuit relation with said load circuit and disposed to be responsive to current flow variation therein, a phase split circuit comprising 30 an inductance element and a resistance element, one of which is variable to shift the phase angle of the grid voltage with respect to the anode voltage of said rectifiers by 180 degrees, 35 said elements being connected in series circuit relation for energization to said current source; a grid transformer having a primary winding connected between the common connection between said inductance element and resistance element and a neutrol point on said source to 40 which said phase split circuit is connected and a secondary winding having a mid-tap, the terminals of said last named secondary winding being connected to the control grids of said 45 rectifiers and the mid-tap thereof being connected to said cathodes; and operating means interconnecting said current sensitive device and the variable element of said phase split circuit.
15. In a regulating system for devices such as 50 series incandescent lamps, glow and arc discharges requiring a substantially constant direct current for circuit stability, in combination, an anode transformer having a primary winding connected to an alternating current supply and a secondary winding, a pair of grid controlled arc 55 rectifiers connected to said secondary winding for supplying direct current to the load circuit, a current sensitive device sensitive to instantaneous current flow variations, said current sensitive device being connected in series circuit 60 relation with the load circuit, a phase split circuit energized from said alternating current supply for energizing the grids of said arc rectifiers, said phase split circuit comprising a network of variable inductance and resistance, one of which 65 is controlled by said current sensitive device to vary the phase of the grid voltage with respect to the anode voltage to control the current flow through said rectifiers in such manner as to hold the current constant in the load circuit from 70 full load to short circuit or zero load.

HUGH E. YOUNG.
